 The Pusey & Jones Corporation, Wilmington,
 Del., a corporation of Delaware

Application October 24, 1941, Serial No. 416,417

11 Claims. (Cl. 34—124)

This invention relates to improved fluid-tight joints between rotatable and non-rotatable members. More particularly, in the adaptation shown in the accompanying drawings, the invention is concerned with a fluid-tight joint construction for the steam and condensation water return lines for drying rolls used in paper mills.

In accordance with standard practice, large steam heated drying rolls in paper mills are carried by hollow journals supported for rotation in fixed bearings carried by the roll stands. Steam for heating the rolls is introduced through the hollow journals, and water of condensation formed in the rolls is withdrawn through pipes extending coaxially through the hollow journals, the pipes being mounted for rotation with the journals in some cases and being non-rotatable in others. Various means have been employed in the past for establishing a steam tight joint between surfaces associated with the rotatable journals and stationary steam conducting casings. Also, similar means have been provided for establishing fluid-tight joints between the coaxial condensation water return pipes and stationary discharge pipes. Since the sealing means employed in such constructions necessarily are subjected to friction, by reason of relative movement between the elements to be sealed, the sealing means are subject to wear and must be replaced from time to time, in order to maintain the joints fluid-tight.

The primary object of the present invention is to simplify joint constructions of the type referred to. More particularly, the invention aims to provide a construction facilitating removal and installation of the parts to facilitate replacement of the sealing means normally subjected to wear.

A further object of the invention is to provide a fluid-tight joint construction that may be removed from the elements to be sealed and replaced thereon with the utmost speed, to the end that the apparatus with which the joint is associated may be out of commission for only a minimum period of time.

A further object of the invention is to provide a construction wherein one set of elements, including worn parts, may be readily and expeditiously removed and a new set of elements, including replacement parts, substituted in a minimum of time and with little effort.

A further object of the invention is to provide a joint construction wherein the pressure applying means for the sealing elements may be accurately adjusted, before the joint assembly is installed in operative relation to the other elements.

A further object of the invention is to provide a joint construction including an assembly that may be removed and replaced, for the substitution of new parts for old, without performing any plumbing operations, such as breaking pipe joints, threading new pipes, installing new pipes in place of old ones or the like.

A further object of the invention is to provide, in a paper drying roll construction, a joint assembly that may be removed by axial movement relative to the roll, replaced by a similar movement in the opposite direction and bolted in position, without disconnecting any pipe fittings or otherwise disturbing the steam and condensation water return lines.

Other and further objects and advantages of the invention will be apparent to those skilled in the art from a consideration of the following description of certain embodiments of the invention, shown by way of illustration in the accompanying drawings, in which:

Figure 1 is a side elevation of a joint in accordance with the present invention, shown in association with a hollow journal and supporting bearing for a paper drying roll.

Figure 1a is a side elevation, similar to Figure 1, on a reduced scale, showing a jack screw arrangement.

Figure 2 is a vertical longitudinal section of the device of Figure 1, on an enlarged scale.

Figures 3, 4, 5 and 6 are sections taken on correspondingly numbered section lines on Figure 2.

Figure 7 is a section on line 7—7 of Figure 1.

Figure 8 is an end elevation, looking from the right of Figure 1.

Figures 9, 10 and 11 are sections taken on correspondingly numbered section lines on Figure 1.

Figure 12 is a vertical section on line 12—12 of Figure 9.

Figure 13 is a vertical section on line 13—13 of Figure 1.

Figure 14 is a vertical longitudinal section, similar to Figure 2, showing a modification.

Figure 15 is a section on line 15—15 of Figure 14.

Figure 16 is an end elevation of the device shown in Figure 14, and

Figure 17 is a detail, plan view of the right-hand end of Figure 14.

In the paper-making art, it is of the maximum importance that the paper-making machine and all of the other machines in the line be operated as continuously as possible, with a minimum of interruptions, and that each shut-down for repairs or the like be for as short a duration as

possible. In some mills, it has been calculated that a shut-down results in a net loss of approximately six dollars per minute. In standard paper-making plants, each line, behind the press rolls, has a great plurality of steam heated drying rolls over which the web of paper passes, to remove the water therefrom, before it is calendered. In some cases, there are as many as one hundred or more rolls, and each necessarily has associated therewith, a fluid-tight joint and a condensation water return joint. When the sealing members associated with the joints become worn, the entire line, from the Fourdrinier machine to the last calender roll, must be stopped, while the joints are repaired, by the replacement of new sealing rings or the like. With prior art joint constructions, this operation normally requires an interruption of the plant of from six to eight hours, with a corresponding loss in the output of the mill.

The principal cause of this substantial delay in repairing a drying roll joint is the necessity for performing a real plumbing job, including the disconnection of the steam and water pipes from the joint casing, refitting the pipes in a new casing and re-connecting the pipes to the supply lines. The fluid-tight joint assemblies of the prior art must be removed from the journal and the axial water pipe by axial movement relative thereto, but this operation cannot be performed until the lateral pipe connections are removed.

The present invention provides a novel construction wherein the joint assembly may be removed and replaced by axial movement relative to the roll, without disconnecting or otherwise disturbing the steam and return water pipes. In fact, the joints may be removed and replaced while the rolls are kept running, by closing appropriate steam and water valves.

As shown in Figure 1, a hollow drying roll journal 20 is mounted in a bearing 21 carried by a bearing support 22 which may be a part of the roll stand, the journal being held in place by a bearing cap 23 of conventional design. A steam and water manifold or bracket 25 has a flange 26 bolted to a seat 27 carried by the bearing support 22, the position of the manifold being accurately determined by shims 28, interposed between the flange 26 and the face of the seat 27, and by dowel pins 26a.

The manifold has an upper flange 29 provided with an upper face 30, preferably plane, and in any case disposed in parallel relation to the journal axis.

Steam and condensation water return pipes 31, 32 are secured by pipe thread joints in downwardly facing hollow bosses 33, 34, forming an integral part of the manifold 25, the internal passages of which will be described below.

A joint assembly comprising a casing indicated generally at 35 has a flange 35' provided with a lower face 36 mating with the face 30 of the manifold 25 and is secured thereon by bolts 37. The joint assembly, including the casing 35 establishes communication between the water and steam passages in the manifold 25 and the water and steam passages associated with the journal, in a manner now to be described.

Referring to Figure 2, an axially disposed condensation water return pipe 38 extends axially through the hollow interior 39 of the journal 20. This pipe is connected at its inner end to devices of well known type for removing water of condensation from the interior of the drum and, in

the embodiment illustrated, rotates with the drum. The end face of the journal 20 carries a sleeve member 40 having a reduced portion 42, in which a plurality of spacing and centering lugs 43, fast on the pipe 38, are disposed, as illustrated in Figures 2 and 3.

The outer face 45 of the sleeve 40 is disposed in contact with the radial face 46 of a sealing ring 47, constituting a part of the joint assembly and preferably retained in place by a circumferential flange 48, associated with the sleeve 40. The sealing ring may be of any approved type, but preferably made from a graphite and carbon composition. The other radial face 49 of the ring 47 is disposed in contact with the radial face 50 of a non-rotatable sealing ring 51 associated with the joint assembly. The ring 51 is supported by a plurality of coil compression springs 52 surrounding lugs 53 formed on a clamping ring 54 secured to the ring 51 by bolts 55, the other ends of the springs 52 surrounding lugs 56 carried by a similar clamping ring 57 secured to an end flange 58 at the forward end 59 of the joint casing 35 by bolts 60. A metallic Sylphon 61 of well known construction has its ends clamped under the rings 54, 57, thereby providing a gas-tight connection between the casing 35 and the ring 51, yet permitting axial movement of the ring 51 relative to the casing under the influence of the springs 52. The casing 35 extends rearwardly from the forward portion 59 adjacent the flange 58 in coaxial relation to the journal 20 and the pipe 38 and is provided with a transverse partition 65 adjacent its rear end and a downwardly projecting rib or feather 66 at an intermediate point. The partition 65 is centrally apertured and carries a collar 67 having a circumferential shoulder 68 formed therein. One end of a Sylphon 69 is pressed over the shoulder 68 and is secured in place by a soldering or brazing 70, or by any other appropriate means. The collar 67 also carries a plurality of axially projecting pins 71 about which compression springs 72 are coiled.

The pins 71 extend loosely through appropriate apertures 73 in a disc 74 having a peripheral slot 75 embracing the rib 66 to prevent rotation of the disc relative to the casing. The ends of the springs 72 bear against the outer face of the disc 74.

The adjacent end of the Sylphon 69 is connected to the disc by a shoulder 76 and solder or brazing 77, in a manner similar to the other end of the Sylphon.

A sealing ring 78, preferably of carbon and graphite composition, is carried adjacent the opposite face of the ring 74 by a circumferential flange 79. The other face of the ring 78 is disposed in contact with the radial face 80 of a collar 81 fast on an intermediate, screw-threaded portion 82 of the pipe 38 and held in place by a lock nut 83. It should be noted that the outer end 38' of the pipe 38 is of reduced diameter and extends through the rings 78, 74 and the collar 67 in spaced relation, and is in communication with the chamber 65, defined by the partition 65.

The main interior chamber 85 of the casing 35 which communicates with the interior of the Sylphon 61 and thence with the hollow interior 39 of the journal 20 has a downwardly extending passage 86, opening through the lower face 36 of the joint assembly by a port 87.

The chamber 65' adjacent the end of the casing 35 is in communication with a forwardly extending passage 88, disposed behind the chamber 65, as viewed in Figures 1 and 2, and to the

right thereof as viewed in Figures 5 and 6. A spigot 95 may be opened whenever it is desirable to discharge water or air from the chamber 90. At its forward end, the chamber 90 turns downwardly and provides a passage 91 opening in a port 92 through the lower surface 36 of the casing 35, the ports 92 and 81 being separated by a partition 93. Thus, the steam and water passages in the joint assembly are isolated from each other and communicate at their inner ends with the hollow interior of the journal and the condensation water return pipe 38 and at their outer ends with ports 81 and 92 in the lower plane face 36 of the joint assembly casing 35.

The manifold 25 similarly has independent steam and water passages, leading from the bosses 33, 34 upwardly (Fig. 9) to spaced ports 100, 101 in the plane upper face 30 of the flange 29. As indicated in Figures 9-12, the boss 33 communicates with a rearwardly and upwardly directed passage 102 terminating in the port 100, while the boss 34 communicates with a similar passage 103 behind the passage 102 and terminating in the upwardly facing port 101, the passages being separated by a partition 104. The bosses and passage walls are preferably cast integrally with vertical webs 105, 106 and an inclined web 107, connected to the mounting flange 26. The latter flange has bolt holes 108 therein, for bolts 109 and additional holes 26b for the dowel pins 26a.

The end wall of the manifold 25 has an outwardly projecting web or flange 110, to which an upwardly projecting arm 112 is pivoted by a removable pin 111. The arm adjacent its lower end carries a yoke 113 in which a screw 114 is threaded, with its end in engagement with the face of the flange 110, so that the angular position of the arm 112 may be accurately adjusted about the pivot 111. The upper end of the arm 112 is provided with apertured, bifurcated portions 115, 116, in which there is disposed a transverse plug 117 having a diametric, threaded bore for the reception of a jack screw 118. The jack screw has a ball head 119 disposed within a socket associated with a foot 120 shaped and positioned to bear against the end wall 121 of the casing 59. The end face of the foot 120 preferably fits within a concave socket formed in the end wall 121 to prevent lateral replacement of the parts. The jack screw carries an operating crank 123 on its rear end. The pin 111 may be readily withdrawn, to permit removal of the entire jack assembly, after it has performed its function, as hereinafter explained.

In the initial installation of the apparatus of the present invention, the manifold 25 is mounted upon the seat 27 of the bearing stand 22 in accurately predetermined relation to the end face of the journal 20. This is preferably accomplished by the use of a template, having a vertical flange adapted to be secured to the end of the journal 20 by the bolts that eventually hold the sleeve 40 thereon. The template also has a horizontal flange provided with bolt holes positioned on centers corresponding to the centers later assumed by the bolts 37. The manifold 25 is bolted to the horizontal flange by bolts extending through the last-mentioned holes, and the space, if any, between the flange 26 of the manifold and the seat 27 is filled with shims. The bolts 109 are then drawn up to secure the manifold in position. It will be understood that there is sufficient clearance between the bolts 109 and the bolt holes 108 to allow relative movement be-

tween the manifold 25 and the seat 27, so that the manifold may be accurately adjusted relative to the journal before the bolts 109 are drawn up. In order that this position may not be accidentally disturbed, holes are drilled in the seat 27 by a conventional steel drill inserted through the dowel openings 26b. Dowel pins 26a are then driven through the holes 26b into the aligned holes in the bearing support, whereby the position of the manifold 25 is permanently maintained. The steam and water pipes 31, 32 may be connected to the manifold at any time, either before or after the template is removed.

The sleeve 40 is next mounted upon the end face of the journal 20 by its bolts and the sealing ring 47 positioned against the end face thereof. The collar 81 and lock nut 83 are appropriately secured on the threaded portion 82 of the pipe 38.

The entire joint assembly with the sealing elements and the resilient means thereof in position is next slipped over the end of the pipe 38, until the flange 35' rests upon the flange 29. The jack screw arm is mounted upon the flange 110 and the screw 114 adjusted to align the jack screw 118 with the casing 35. The crank 123 is then turned, so that the joint assembly as a whole is forced axially toward the journal, compressing the coil springs 52 and 72 and causing the lower plane face 36 of the flange 35' to slide along the surface 30 of the flange 29 until the bolt holes in the two flanges are in alignment, whereupon the bolts 36 are inserted and tightened, to hold the assembly in place. The jack screw 118 may then be backed off and the jack assembly removed, by withdrawing the pin 111.

The form of the invention shown in Figures 14-16 differs from the first form primarily in that it accommodates a non-rotatable condensation water return pipe 38a. With such a pipe, the use of a sealing assembly of the type provided in the first form of the invention by rotatable and stationary rings 81 and 74 and the sealing ring 78 is unnecessary. The joint for the steam passage is substantially identical to that previously described, and comprises a flange 58a on the casing 59a, a Sylphon 61a connecting the flange to a ring 51a, a carbon-graphite disc 47a and a sleeve 40a carried by the hollow journal 20a. The manifold 25a may be identical to the one previously described, and may be mounted in the same way.

The outer end portion 125 of the casing 59a has a transverse partition 126 and an end wall 127, defining an inner, condensation water chamber 128 communicating with a passage 90a, extending forwardly and downwardly and terminating in a port 92a, in registry with a port 101a in the manifold, as previously described in connection with the first form of the apparatus.

A sleeve 130, threaded on the end of the pipe 38a, has an outwardly projecting, circumferential flange 131 disposed opposite the partition 126, with a gasket 132 interposed therebetween, to make a fluid seal between the sleeve and the casing.

The sleeve 130 at its outer end is integral with a spider 135 connected to a shaft 136, extending outwardly through an aperture in the end wall 127 and secured in fluid-tight relation thereto by a gland comprising packing 137 and a ring 138, secured to the end wall by bolts 139, adapted to place the packing under compression. A cap 140 surrounding the shaft 136 has radial serrations mating with similar serrations 141 on the

end face of the end wall 127. A nut 142 on a threaded portion 143 of shaft 136 may be tightened, to draw the sleeve 130 and the flange 131 thereof toward the partition 126, to compress the gasket 135 and thereby provide a steam-tight joint. If desired, a key 143a may be disposed in mating slots in the shaft 136 and the cap 140, to prevent relative rotation of those parts, by permitting axial movement of the cap 140 along the shaft 136, to disengage the serrations 141, when desired, in order to change the angular position of shaft 136 and pipe 38a. In many cases, the key 143a may be omitted as the nut 142 may be relied upon to prevent inadvertent rotation of the shaft 136 relative to the cap 140.

The outer end of the shaft 136 is provided with angularly disposed flattened surfaces 145, 146 and with a substantially semi-cylindrical surface 147, adapted to receive a specially shaped wrench 148, so that the shaft and the pipe 38a may be held against inadvertent rotation when the nut 142 is tightened. It is important with stationary syphon pipes that they be maintained in accurately predetermined annular position, with the water removing devices thereof substantially at the bottom of the drying roll, or at angle, if desired, according to the speed of the drying roll. The point provided by the junction of the flattened sides 145, 146, provides a good indication of the correct position of the parts.

When it is desired to remove the joint assembly shown in Figures 14-16, it is simply necessary to remove the nut 142, wrench 148 and bolts 31a, whereupon the assembly may be moved axially away from the hollow journal, leaving the sleeve 130, spider 135 and shaft 136 in position on the pipe 38a. After a new sealing ring 47a or any other part has been substituted for a worn one, the assembly may be replaced by a movement in the opposite direction. If desired, a jack screw assembly similar to that employed with the first form of the invention may be used to force the joint casing and associated parts into proper position.

It will thus be seen that the present invention provides a novel form of joint that may be installed and removed with great facility, without disturbing any pipe connections or the like.

Although the invention has been described in considerable detail, by reference to the two preferred forms shown in the accompanying drawings, it must be understood that the invention is not limited to the details of construction thereof, but covers all modifications coming within the scope of the appended claims and their equivalents.

I claim:

1. In combination, a paper drying roll, a rotatable hollow journal therefor having steam and water passages leading therethrough, a supporting bearing for the journal, a fixed manifold independent of the bearing and having steam and water passages permanently connected to steam and water lines, and a joint assembly separate from and independent of the bearing and comprising a casing removably carried in normally fixed relation by the manifold and having passages communicating respectively with the passages in the journal and in the manifold, a packing member between the casing and the rotatable journal, and resilient means non-rotatably carried by the casing for urging the packing member against a surface rotating with said journal, said casing and said resilient means being supported on said mani-

fold for ready removal therefrom and from the bearing for replacement of said packing member without disturbing the support of the journal in the bearing or the connections of said steam and water lines with the manifold.

5. The combination with a paper drying roll having a hollow journal providing a steam passage leading to the interior of the roll, a fixed bearing for the journal and an axial condensation water return pipe extending outwardly through the journal, of a manifold supported in fixed position relative to the bearing and having a face disposed in parallel relation to the roll axis, said manifold having independent steam and water passages opening through said face and permanently connected at their other ends to steam and water pipes, and a joint assembly 10 separate from and independent of said bearing and comprising a casing having a face parallel to and supported upon the face of the manifold, whereby the assembly may be removed from the manifold by sliding movement axially of the roll, without affecting said bearing, said casing having a water passage registering with the manifold water passage and connected to said axial pipe, and a steam passage registering with the manifold steam passage, said assembly further comprising a rotatable seal connecting the steam passage to the hollow journal, and non-rotatable 15 resilient means carried by the casing and urging the seal against the journal.

3. The combination with a paper drying roll having a hollow journal providing a steam passage leading to the interior of the roll, a fixed bearing for the journal and an axial condensation water return pipe rotatable with and extending outwardly through the journal, of a manifold supported in fixed position relative to the bearing and having a face parallel to the roll axis, said manifold having independent steam and water passages opening at one of their ends through said face and permanently connected at their other ends to steam and water pipes, and a joint assembly 20 separate from and independent of said bearing and including a casing having a face parallel to and supported upon said face of the manifold, whereby the assembly may be removed from the manifold by sliding movement axially of the roll, while leaving the journal supported by the bearing, said assembly comprising a water passage registering with the manifold water passage, a rotatable seal connecting the water passage to the axial return water pipe, a steam passage registering with the manifold steam passage, and a rotatable seal connecting the steam passage to the hollow journal.

4. The combination with a paper drying roll having a hollow journal providing a steam passage leading to the interior of the roll, a fixed bearing for the journal and an axially disposed, non-rotatable condensation water return pipe extending through the journal in spaced relation to the inner wall thereof, of a manifold supported in fixed position relative to the bearing and having a face disposed parallel to the roll axis, said manifold having independent steam and water passages opening at one of their ends through said face and permanently connected 25 to steam and water pipes at their other ends, and a joint assembly separate from and independent of said bearing and having a face parallel to and supported upon said face of the manifold, whereby the assembly may be removed from the manifold by sliding movement axially of the roll, while leaving the journal supported by the bearing, said assembly comprising a water passage registering with the manifold water passage, a rotatable seal connecting the water passage to the axial return water pipe, a steam passage registering with the manifold steam passage, and a rotatable seal connecting the steam passage to the hollow journal.

the roll, while leaving the journal supported by the bearing, said assembly having a water passage registering at one of its ends with the manifold water passage and rigidly connected at its other end to the axial return water pipe, a steam passage registering at one of its ends with the manifold steam passage and connected at its other end to the hollow journal by means including a ring seal, a sylphon and spring means for applying axial sealing pressure to the ring seal.

5. The combination with the hollow journal for a paper drying roll, of a bearing surrounding said journal, a supporting standard for the bearing, a manifold carried by said standard in predetermined, fixed position relative to the bearing and the journal, said manifold having a face parallel to the roll axis and independent steam and water passages opening at one of their ends through said face and at their other ends in external pipe connections, steam and water pipes independent of said standard, permanently connected to said external pipe connections, and a joint assembly comprising a casing having a face parallel to and supported upon said face of the manifold for removal therefrom by sliding movement in an axial direction, said assembly having steam and water passages therein registering at one of their ends with the passages in the manifold and at their other ends with the journal.

6. The combination with a hollow journal for a paper drying roll, of a bearing supporting said journal, a supporting standard for the bearing, fixed steam and water pipes pipes separate from and independent of said standard and said bearing, an independent manifold carried by said standard in predetermined, fixed position relative to the bearing and the journal, said manifold having independent steam and water passages permanently connected at one of their ends to said fixed steam and water pipes and opening at their other ends through an exterior face of the manifold, and a joint assembly comprising a casing having a face supported upon the face of the manifold for ready removal therefrom independently of the standard, bearing and journal, said assembly having steam and water passages therein registering at one of their ends with the passages in the manifold and at their other ends with the journal.

7. For use with a steam heated paper drying roll of the type having a hollow journal mounted in a bearing carried by the roll stand, a manifold for steam and for water of condensation, said manifold comprising means for mounting the same upon the roll stand in predetermined fixed relation to the bearing, but in non-supporting relation with respect thereto said manifold having surface shaped and positioned to extend parallel to the journal axis when the manifold is so mounted, and walls in the manifold independent of the mounting means defining a pair of internal passages terminating at their outer ends in hollow bosses adapted to be permanently connected to steam and condensation water return pipes independent of and spaced from the roll stand and terminating at their inner ends in ports opening through said surface, said surface having fastening means associated therewith whereby a joint assembly may be mounted on said manifold surface to establish communication between said ports and the hollow journal.

8. For use with a steam heated paper drying

roll assembly of the type including a roll stand, a bearing carried thereby, a drying roll having a hollow journal mounted in said bearing and having steam and condensation passages extending therethrough, and steam and condensation water return pipes independent of and supported in fixed relation to the roll stand; a manifold comprising means for connecting the same to and supporting the same from the roll stand in predetermined fixed relation to the bearing but in non-supporting relation with respect thereto, a joint supporting surface on the manifold, a pair of pipe receiving bosses spaced from said surface and adapted to be permanently connected to said steam and condensation water return pipes, and walls within said manifold defining independent steam and condensation water return passages leading from said bosses and terminating at their other ends in ports opening through said joint supporting surface, whereby a joint assembly may be fastened upon said joint supporting surface of the manifold to establish communication between said ports and the steam and condensation water passages associated with said hollow journal.

9. In combination, a drying roll having a hollow journal, a supporting bearing therefor, a condensation water return pipe extending axially through and beyond the hollow journal in spaced relation thereto and rotating therewith and defining an annular steam passage, a sealing surface rotating with the hollow journal and normal to the roll axis, a second sealing surface rotating with the pipe and normal to the roll axis, a fixed steam and water manifold separate from and independent of said bearing and having a joint assembly supporting face having steam and water ports opening therethrough, and a joint assembly comprising a casing having a face supported upon and mating with the manifold face, steam and water passages registering with the manifold ports and with the journal passage and pipe, non-rotatable sealing surfaces parallel to and facing the first-mentioned sealing surfaces, sealing rings between the mutually facing sealing surfaces, and resilient means for establishing pressure contact between said sealing surfaces and said rings, said mating faces on the manifold and assembly serving to permit installation of the assembly upon the manifold by movement axially of the roll axis.

10. In combination, a drying roll having a hollow journal, a supporting bearing therefor, a condensation water return pipe extending axially through and beyond the hollow journal in spaced relation thereto and rotating therewith and defining an annular steam passage, a sealing surface rotating with the journal and normal to the roll axis, a second sealing surface rotating with the pipe and normal to the roll axis, a fixed steam and water manifold separate from and independent of said bearing and having a plane face parallel to the roll axis and steam and water ports opening therethrough, and a joint assembly comprising a casing having a face parallel to and mating with the manifold face, steam and water passages registering with the manifold ports and with the journal passage and the pipe, non-rotatable sealing surfaces parallel to and facing the first-mentioned sealing surfaces, and sealing rings between the mutually facing sealing surfaces, whereby the sealing assembly may be installed on the manifold by sliding movement of the

assembly face along the parallel face of the manifold axially of the roll.

11. In combination, a drying roll having a hollow journal, a supporting bearing therefor, a condensation water return pipe extending axially through and beyond the hollow journal in spaced relation thereto and rotating therewith and defining an annular steam passage, a sealing surface rotating with the journal and normal to the roll axis, a second sealing surface rotating with the pipe and normal to the roll axis, a fixed steam and water manifold separate from and independent of said bearing and having a face parallel to the roll axis and steam and water ports opening therethrough, and a 15

joint assembly comprising a casing having a face parallel to and mating with the manifold face, steam and water passages registering with the manifold ports and with the journal passage and pipe, non-rotatable sealing surfaces parallel to and facing the first-mentioned sealing surfaces, sealing rings between the mutually facing sealing surfaces, and resilient means for establishing pressure contact between said sealing surfaces and said rings, said parallel, mating faces on the manifold and assembly serving to permit installation of the assembly upon the manifold by sliding movement axially of the roll.

SAMUEL M. BRATTON.
